FOLDING BED.

APPLICATION FILED MAY 10, 1920.

Patented Jan. 25, 1921.

2 SHEETS—SHEET 2.

INVENTOR.

William H. Minnick.

BY *Victor J. Evans*
ATTORNEYS.

UNITED STATES PATENT OFFICE.

WILLIAM H. MINNICK, OF SAN FRANCISCO, CALIFORNIA, ASSIGNOR OF ONE-FIFTH TO GEORGE F. SEIBERT, ONE-FIFTH TO JULIUS HAWKINS, ONE-FIFTH TO ARTHUR A. FRISBEE, AND ONE-FIFTH TO ARTHUR MINNICK, ALL OF SAN FRANCISCO, CALIFORNIA.

FOLDING BED.

1,366,820.

Specification of Letters Patent. Patented Jan. 25, 1921.

Application filed May 10, 1920. Serial No. 380,260.

To all whom it may concern:

Be it known that I, WILLIAM H. MINNICK, a citizen of the United States of America, residing at San Francisco, in the 5 county of San Francisco and State of California, have invented new and useful Improvements in Folding Beds, of which the following is a specification.

This invention relates to a new and useful 10 improvement in folding beds, and has particular reference to the type of bed known as "knockdown" beds.

One of the objects of this invention is to create a bed which will have all the appearances of a davenport when closed, and will have all the advantages of a spring bed when opened.

An important object of this invention is to produce a structure of such a design that 20 the various parts may be detached one from another for convenience in storing or shipping.

A further object of this invention is to provide a folding bed which has all the 25 advantages of those in use today and yet can be operated and entirely controlled by an improved type of hinge, which is the only mechanism required in the operation of folding a davenport into a bed, or vice 30 versa.

A further object of this invention is to provide a bed which will be cheap to manufacture and consequently come within the reach of the average individual, it being a 35 well known fact that davenport beds of this nature are now beyond the reach of the poorer classes.

An additional object of this invention is to provide a folding portion, which will 40 accommodate the folding of a standard mattress without crushing the same, and thus forming hollow spots in the mattress.

A still further object of this invention is to provide a davenport bed of the above 45 mentioned character, which is simple in construction, compact in arrangement of parts, easy to operate, strong, durable, and in addition thereto makes a very ornamental appearance.

50 Other objects and advantages of this invention will be apparent during the course of the following description.

In the accompanying drawings forming

a part of this specification and in which like numerals are employed to designate like parts throughout the same, Figure 1, is a perspective view of my bed in an extended position and ready to receive a mattress.

Fig. 2 is a perspective view of my bed in its closed position forming a davenport. 60

Fig. 3 is a fragmentary perspective view of the end of the bed showing the manner of securing a mattress thereon.

Fig. 4, is a view similar to Fig. 3 showing the mattress securing means folded back 65 so as to disengage the mattress.

Fig. 5 is an elevation of the hinged member.

Fig. 6 is an end elevation of the hinge looking in the direction of the arrow of 70 Fig. 5.

Figs. 7, 8, and 9, are detail views of my section attaching means.

Fig. 10 is a perspective view of an attaching brace. 75

Fig. 11 is a detail view of a pivot pin and,

Fig. 12 is an end elevation of the pin shown in Fig. 11.

In the drawings, wherein for the purpose 80 of illustration is shown a preferred embodiment of my invention, the numeral 5 designates a panel, which will form the back or head of my bed; and the numerals 6 and 7 designate side pieces or members, which are 85 attached to the panel 5 by means of braces 8. These braces 8 are best shown in Fig. 10 and, consist of an angle iron having openings 9, which allow the same to be attached to the panel 5 and are provided with a slot 90 11 which allows of a removable connection for adjustment to the members 6 or 7. These side members 6 and 7 each carry an arm portion 12 and 13, with the usual depending slats 14, which slats have their lower 95 ends positioned in a base-board 16.

The forward ends of these base boards 16 are attached by a cross bar 17, which cross bar is held to the members 16 by means of hooks 18 best shown in Fig. 7. These hooks 100 18 are adapted to project through openings 19 formed in a plate 21, which plate 21 is secured to the base-boards 16 at their inner edges. A suitable orifice 22 is provided for the accommodation of the ends of the hooks 105 18.

The numeral 23 designates a top panel adapted to be carried between the upper ends of the side members 6 and 7, and for the purpose of simplicity, I have shown simple pivot pins 24 best illustrated in Fig. 11, which pivot pins are adapted to be attached to the panel 23 and to have their pintle portion 26 project into the ends 6 and 7. This panel 23 carries a cushion 27 attached thereto at a suitable angle, the purpose of which is obvious.

At 28 I have shown a pivoted latch, which has engagement with a pin 29, the purpose of which is to retain the panel 23 and its cushion 27 in the position shown in Fig. 1 while the bed is being occupied.

The spring or mattress supporting portion of my bed is preferably made in two sections, designated by the numerals 31 and 32, so that the section 31 will lie between the base-boards 16 and be attached thereto by means of fastening elements 16', while the other section 32 will extend outwardly from said section 31, but in the same plane therewith. These sections are hinged together as shown in Fig. 1 by two substantially L shaped hinged members 33 and 34. This hinge is best shown in Figs. 5 and 6, where it will be noted that the L shaped portion 33 has two arms of substantially the same length, one of said arms being provided with openings for the reception of screws or bolts, and the other of said arms carrying a pivot at its extremity.

It will be noted that the other L shaped member 34 is provided with an off-set 35 and that one arm is substantially twice as long and provided at its central point with a pivotal connection. By this construction it will be noted that the member 34 may rotate upon the pivot point 36 through an arc of 180 degrees and as the L shaped member 34 is attached to the spring section 32 the same will be caused to fold over and upon the spring section 31. This folding is assisted by the action of springs 37 having their outward ends connected to eye bolts 38 carried at the extremity of the L shaped member 34.

Attention is called to the fact that by employing this improved type of hinge, as just described, I have provided simple mechanism which completely controls the whole conversion of the davenport into a bed, or vice versa. This improved type of hinge obviates the use of complicated mechanism as employed in folding beds in use today, and it will be observed that my improved type of hinge not only makes the operation of the device simple, but it is also

strong and durable enough to withstand the strain occasioned in operating devices of this type.

The numeral 39 designates a cushion attached to the spring section 32, while a 65 looped element is shown at 39' to enable the user of the bed to lower or lift the device and thus start the operation of converting the device into a bed or davenport. The numeral 41 designates the legs for supporting the outer end of the spring section 32.

The numeral 42 designates a clamping board which is pivotally attached to the sides of the spring section 32 and is held in contact with the end of the mattress, as 75 shown in Fig. 3, by means of a spring 43 located at both ends. These springs are of such construction that they allow the board 42 to take the position shown in Fig. 4 when the bed is occupied, thereby allowing the 80 entire mattress to be utilized.

It will thus be seen that I have devised a folding bed which has all the advantages of an ordinary bed and one which will fold owing to my hinge construction shown at 33 85 and 34 without damaging an ordinary mattress, which is not possible with the common type of folding bed or divan.

It is to be understood that the form of my invention herewith shown and described, 90 to be taken as a preferred example of the same, and that various changes in the shape, size, and arrangement of parts may be resorted to without departing from the spirit of the invention or the scope of the sub- 95 joined claims:

Having thus described the invention, I claim:

1. In a folding bed, a spring section, an L shaped member attached to the opposite 100 sides of said section at a point adjacent to the corners thereof, a second spring section, L shaped members attached to said second mentioned spring section, said second mentioned L shaped members being pivotally 105 attached to said first mentioned L shaped members and an extension thereof on said second mentioned L shaped members.

2. In a folding bed, the combination of a plurality of spring sections, said sections 110 having their abutting ends in alignment one with another, L shaped members attached to the abutting corners of said spring sections, one of said L shaped members being longer than its adjacent L shaped member and a 115 pivotal connection between said long and said short L shaped member.

In testimony whereof I affix my signature.

WILLIAM H. MINNICK.
